UNITED STATES PATENT OFFICE.

WILLIAM H. McCLELLAND, OF HUNTINGDON, PENNSYLVANIA, ASSIGNOR TO DAVIS
BRICK MACHINERY COMPANY, OF MOUNT UNION, PENNSYLVANIA.

HOPPER.

Application filed June 2, 1926. Serial No. 113,279.

My invention relates to improvements in brick making machines and is more particularly directed to means employed therein for depositing green mud, from which the 5 brick is formed, into molds as they are moved toward the baking furnace, or their discharge position.

It is the object of my invention to provide means for depositing within each mold a 10 certain amount of green mud, and means for operating said first mentioned means from suitable driving or driven shafts of the machine proper.

A further object of my invention is to 15 provide a plurality of hoppers, each having a movable bottom, so positioned within the machine that as the molds travel thereunder green mud is deposited therein.

Still another object of my invention is to 20 provide means for permitting the ready discharge of the green mud from the hopper without the danger of the mud sticking thereto and breaking.

Heretofore, in hoppers of this character 25 it has usually been the custom to close the same with hinged doors, which in their actual use I have found to be more or less unsuccessful due to the fact that the doors are not positioned in such a manner as to permit the mud to drop freely from the 30 hopper without the danger of the mud following the doors in their movement, thereby breaking the batch of mud and creating a condition that is undesirable. It is therefore 35 the object of my invention to provide a hopper, and its closing means, that will eliminate this fault. To accomplish this feature I have provided a hopper having downwardly diverging side and end walls, thus 40 eliminating the possibility of mud sticking thereto. The bottom of the hopper is closed by a pair of downwardly converging plates 45 which are pivoted remote from the discharge opening of the hopper, thus permitting the plates to swing away from the opening and change their angle during such movement so that green mud contained within the 50 hopper will not stick thereto and be broken when the plates are moved free of the opening.

Another object of my invention is to pro-

vide automatic means for returning the movable bottom of the hopper back to its active position.

With the above and other objects in view, 55 the nature of which will be more fully understood from the description hereinafter, my invention consists in the novel construction and arrangement of parts which will be more fully hereinafter set forth and defined 60 in the claims.

In the accompanying drawings:—

Figure 1 is a side elevation of my improved mold filling hoppers.

Figure 2 is an end elevation of the same. 65

Figure 3 is a top plan view of one of the hoppers and its operating means.

Figure 4 is a vertical sectional view taken through one of the hoppers.

Figure 5 is a sectional view taken on the 70 line 5—5 of Figure 4.

Figure 6 is a detail view of the operating arm, and

Figure 7 is a detail view showing a modification of the hopper operating means. 75

Referring to the accompanying drawings in detail, wherein like reference characters denote corresponding parts throughout the several views, the numeral 1 indicates, in general, the frame of a brick making machine, the same having mounted therein my improved hoppers and the operating means therefor. The hoppers A are so positioned within the machine, with respect to the mold carrying conveyor, that material which is deposited within each hopper may be readily transferred to the molds, and it is my intention to provide a hopper of a size somewhat narrower than that of the molds, thus preventing the material from dropping out of the limits of the molds and to allow the air to be excluded. 80

The frame 1 is provided with a plurality of side angle irons 2 between which I have mounted my improved hoppers A, the same 85 adapted to overlie the mold carrying means.

As disclosed in Figure 4, each hopper A is composed of a pair of spaced end plates 3 which are connected adjacent their edge portions, and near the upper portion thereof, by a pair of spaced and downwardly converging side plates 4, the end portions 90

of which are secured to the plates 3 by angle irons 5. The plates 3 are further connected by a second pair of spaced and downwardly diverging side plates 6, the upper edge of each being positioned under the lower edge of the corresponding upper side plate 4, and the end portion of each plate 6 is likewise secured to the end plates 3 by angle irons 7. As illustrated in Figure 5 it will be noted that the width and length of each hopper increases downwardly toward the discharge opening, thus forming tapering sides to prevent the green mud from sticking thereto.

15 Each hopper A is supported between the side bars 2 by bolts or the like 8 which pass through the upper edge portions of the end plates 3.

20 Positioned upon each side of the hopper are shafts 9 and 9' which are rotatably mounted within suitable bearings 10 secured to the upper face of the side bars 2. In order to permit the shafts 9 and 9' to be positioned somewhat near the side walls of the 25 hopper I have provided within the end plates 3 cutout portions 3' to receive therein the shafts.

That portion of each shaft 9 and 9' which is positioned between the end plates 3 has 30 secured thereto, adjacent each end plate, a bushing 11, and loosely connected to each shaft and between the bushing 11 and the end plate 3 is a pair of downwardly extending arms 12, the lower portions of which 35 are bent inwardly under the discharge opening of the hopper and have secured thereto plates 13 which form the closures for the hoppers. One end portion of each shaft 9 and 9' has secured thereto intermeshing 40 gears 14, so that movement of one shaft will be accordingly transmitted to the other. The other end of the shaft 9 has secured thereto an arm 15, the free end portion of which is pivotally connected to the upper 45 end of a pitman rod 16. The lower end portion of the rod 16 is threaded and adjustably received within a threaded opening provided in the end portion of a weighted arm 17, the rod being locked in its adjusted 50 position by means of a locking nut 18.

The lower portion of the weighted arm 17 is provided with a longitudinally extending slot 19 which receives therein a sliding block 20, the same having passing therethrough, and rotatable therein, the end portion of a shaft 21 which is rotatably mounted within bearings 22 fixed to certain of the uprights of the main frame 1. The outer end of the shaft 21 has fixed thereto a cam 23, the same being retained upon the shaft by a plate 24 having a collar 25 through which passes a locking pin 26. Engageable with the periphery of the cam 23 is a roller 27 which is freely rotatably connected to 65 the arm 17 and positioned above the cam.

In this structure the purpose of the weighted arms 17 is to rotate the shafts in opposite directions, thus closing the hopper.

From the structure hereinabove described it will be readily seen that upon rotation 70 of the shaft 21 movement will be imparted to the cam 23, which in turn will move the arm 17 upwardly upon the block 20, thus causing the shaft 9 to oscillate, and by reason of the fact that the shaft 9 is connected 75 to the shaft 9' by the gears 14, the shaft 9' will likewise oscillate, thereby controlling the closing of the plates 13. To move the plates 13 to a closing position for the hopper I have provided upon each shaft 9 and 9', 80 and fixed thereto, an arm 40 which upon movement of the shafts in one direction will engage the rear edge of the plates 13 and move them to a closing position. When the shafts are again rotated in a reversed direction, the engagement of the arms 40 with the plate 13 is broken and by reason of 85 springs 28 the plates are moved to opening position.

The springs 28 have one end connected 90 to each arm 12 and the other end of same are connected to suitable portions of the main frame 1 while others are connected to a bracket fastened to the frame.

As disclosed in Figure 7 I have illustrated a modification of the means for moving the plates 13, which includes positive means for rotating the shafts in their opposite directions, thus eliminating the use of the weighted arms 17. To this end I have 95 fixed upon the shaft 21 a pair of oppositely positioned cams 30 and 31 between which the arm 17' is positioned and connected to the shaft 21 in the manner described in the preferred form. The opposite side of the 100 arm 17' has fixed thereto rollers 32 which are positioned in such a manner as to engage the periphery of the cams 30 and 31 upon opposite sides of the shaft 21. From 105 this structure it will be clearly apparent that the cam 30, upon its rotation, will move the shafts in one direction, while the cam 31 will move them in another.

In the drawings and the above description I have not illustrated nor described the 115 operation of the mold carrier as it will of course be understood that the same may be in any form and its operation with respect to that of the hopper operating means will be such that will permit the molds to stop 120 under the hoppers to receive therein the green mud. Furthermore, I may employ in this structure means similar to that disclosed in my copending application filed June 2, 1926, and bearing Serial No. 113,280, 125 for holding the hopper closed until at such time as the arms 40 have moved outwardly sufficient to permit the bottom to move under the influence of the springs.

From the foregoing, it is thought that the 130

construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

10 Having thus fully described my invention, what I claim as new, and desire to secure by Letters Patent, is:—

A hopper of the class described comprising vertically disposed end walls, down-

wardly converging side plates connected to 15 said end walls adjacent the upper ends of the former, additional side plates forming continuations of said first mentioned plates, said additional plates gradually diverging from each other from their upper to their 20 lower ends to form an enlarged discharge bottom, and operable means for normally closing the said enlarged bottom of the hopper.

In testimony whereof I affix my signature. 25

WILLIAM H. McCLELLAND.
